UNITED STATES PATENT OFFICE

JACK ROSENTHAL, OF BROOKLYN, NEW YORK, ASSIGNOR TO HENRY LEDERER & BRO., INC., OF PROVIDENCE, RHODE ISLAND, A CORPORATION OF RHODE ISLAND

DESIGN FOR AN AUTOMATIC LIGHTER

Application filed June 14, 1929. Serial No. 31,682. Term of patent 14 years.

To all whom it may concern:

Be it known that I, JACK ROSENTHAL, a citizen of the United States, residing in the city of Brooklyn, county of Kings, and State of New York, have invented a new, original, and ornamental Design for an Automatic Lighter, of which the following is a specification, reference being had to the accompanying drawing, forming a part thereof.

Fig. 1 is a top plan view; Fig. 2 is a side elevation and Fig. 3 is a front edge view of an automatic lighter, showing my new design.

I claim:

The ornamental design for an automatic lighter, substantially as shown.

JACK ROSENTHAL.
